UNITED STATES PATENT OFFICE

2,635,259

LAUNCHING GEAR FOR BOATS

William Edward Morley, Gillingham, Walter Gordon Moore, Birkdale, and William Cameron Rouse, Liverpool, England

Application January 20, 1948, Serial No. 3,346
In Great Britain January 27, 1947

1 Claim. (Cl. 9—38)

1
This invention is for improvements in or relating to launching and lower gear (e. g. lowering gear for ships' lifeboats) of the gravity-operated type comprising a davit arm or the like and a stand and having a multiple pivot arrangement for the davit arm (i. e. of the type in which there are at least two pivots about which the davit arm swings outboard successively). Such launching or lowering gear is hereinafter referred to as a davit of the type specified.

One object of the present invention is to provide a davit or the like of the type specified, in which movement of the davit arm is checked or guided so that the davit head or horn follows a relatively smooth path. In other words, an object of the present invention is to smooth out the step or steps, and thereby the abrupt changes of load which occur in multiple pivot davits as the arm changes from one pivot to another.

Accordingly the present invention provides a gravity davit of the type specified and having, at least, two pivots about which the davit arm pivots outboard successively, characterised by guide means acting on the davit arm to guide it out of truly circular movement about, at least, the first of said pivots and reduce the curvature of the path of movement of the davit arm head to less than what it would have been had the davit arm movement been truly circular about said first pivot, whereby there is a smoothing-out of the movement of the davit arm head as the pivotal support for the arm changes from one pivot to the next. In other words, the sudden changes of direction and load which occur where the arc of movement about one pivot intercepts the arc of movement about another are smoothed out at least to a material extent. Thus, there is a substantially steady load on the wire of the control winch or other gear instead of a sharp change of load at the point of engagement of each succeeding pivot.

In a preferred embodiment of the invention a roller on the davit arm engages a guideway or track on the stand or vice versa.

The invention will be further described, by way of example, with reference to the accompanying diagrammatic drawings which show one embodiment of the invention as applied to a gravity davit of the multiple pivot type. On the drawings:

Figure 1 is a side elevation of the davit,

Figure 2 is a front elevation, and

Figure 3 is a fragmentary detail view of the guide means for the davit arm.

Briefly, the davit shown on the drawings comprises a stand 10, a davit arm 11 and a link 12.

2
One end of the link 12 is pivoted to the stand 10 at 13 (to provide a first or upper fulcrum or pivoting device for the arm) and the other end of the link is pivoted to the davit arm at 14 (to provide a second or lower fulcrum or pivoting device for the arm). The arm 11 carries a keel chock or rest 15 which provides support for the boat b in the stowed position. A stop 16 on the davit stand 10 arrests downward and in-board movement of the link 12 at the end of movement of the davit arm and link about the first fulcrum 13. A further stop-plate 17 halts outboard movement of the davit arm, about the fulcrum 14, at the final extended position of the arm. The davit stand comprises two cheek-plates secured together in spaced-apart relationship and housing the davit arm between them so as to provide good lateral support for the arm.

For the purpose of the present invention it is convenient to provide the lower forward part of the davit stand with an inclined or curved trackway or guide 18 and the davit arm with a roller 19 which is journalled on a horizontal axle 20 on the arm in the neighbourhood of the keel rest 15. In the launching operation, as the arm 11 and link 12 tilt about the first pivot 13 the roller 19 engages with the trackway 18 and constrains the arm to move so that the path of movement of the davit head 11a is defined by the guideway 18 and not solely by the angular or circular movement of the link 12 about the pivot 13. The inclination and length of the guideway 18 is such that there is no sudden "dip" and abrupt change of load as movement of the davit arm changes from that taking place about the first pivot 13 to that taking place about the second or subsequent pivot 14. It will be noted that the inclination of the track 18 to the horizontal is less than that of the link 12 when the latter is in its lowermost position. The roller may leave the trackway some time before the arm completes its full outboard movement. Successive positions of the roller 19 as it moves from the stowed position indicated at A to the fully outboard position indicated at E are indicated at B, C and D and the corresponding positions of the davit head 11a and second fulcrum 14 are similarly marked. The approximate path of movement of the davit head is indicated by the line F. The line G indicates the truly circular path of movement of the davit head if the track 18 and roller 20 are omitted and it will be noted that there is an adverse sudden change of direction at G. 1.

To ensure outboard movement of the davit arm, even when the vessel on which the davit

is fitted has a substantial adverse list, the centre of gravity of the combined mass of the arm 11 and link 12 is arranged so as to be outboard of the pivot 13 even when the arm is in the stowed position and the second fulcrum 14 is arranged to move downwardly and inboard so that the centre of gravity of the arm is outboard of said second fulcrum when the latter is in its lowermost position, i. e. is in the second pivoting position for the arm indicated at D.

It will be appreciated that an obvious mechanical equivalent of the above described arrangement would be to have a roller or the like on the stand arranged to engage a cam-profile or track on the davit arm to constrain the head of the latter to move in the required path.

In the stowed position the davit arm may rest directly or indirectly on the upper face of the link 12 or on the upper pivot 13.

We claim:

A gravity davit comprising a davit stand having a downwardly and outwardly extending trackway, fixed pivot means at the upper portion of said stand, a link pivotally suspended from said pivot means, a davit arm having a davit head at one end and being pivoted at the other end to the lower free end of said link, stop means at the lower portion of said stand below and outboard of said pivot means to limit inboard swinging of said link to a position extending downwardly and outboard from said pivot means, said davit arm being movable between a stowed inboard position and an extended outboard position and being guided dur-

ing the inboard portion of its movement by the swinging of said link about said pivot means relative to and outboard of said stop means and during the outboard portion of its movement by pivoting relative to said link while said link is stationary against said stop means, a roller on said davit arm and engageable with said trackway to support said arm during the inboard portion of its movement and while said link is spaced from said stop means, whereby tracking of said roller on said trackway causes smooth translational movement of said arm during the swinging of said link relative to said stop means and guides the davit head in a smooth path that is tangent to the arc about the pivot between the davit arm and link when the link is stationary against said stop means.
